US00D816760S

(12) **United States Design Patent** (10) **Patent No.:** **US D816,760 S**
(45) **Date of Patent:** **** May 1, 2018**

(54) **STAND**

(71) Applicant: **SZ DJI Osmo Technology Co., Ltd.,**
Shenzhen (CN)

(72) Inventors: **Haibin Zheng**, Shenzhen (CN); **Min Kim**, Shenzhen (CN)

(73) Assignee: **SZ DJI Osmo Technology Co., Ltd.,**
Shenzhen (CN)

(**) Term: **15 Years**

(21) Appl. No.: **29/578,550**

(22) Filed: **Sep. 22, 2016**

Related U.S. Application Data

(63) Continuation of application No. 29/540,664, filed on Sep. 25, 2015, now Pat. No. Des. 772,326.

(51) **LOC (11) Cl.** **16-05**

(52) **U.S. Cl.**

USPC **D16/244**

(57) **CLAIM**

The ornamental design for a stand, as shown and described.

DESCRIPTION

FIG. 1 is a top front perspective view of a stand showing the claimed design;

FIG. 2 is a bottom rear perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines in the figures show portions of the stand that form no part of the claimed design.

1 Claim, 8 Drawing Sheets
